UNITED STATES PATENT OFFICE.

HIRAM A. DOW, OF BATTLECREEK, MICHIGAN.

MESSAGE DEVICE.

SPECIFICATION forming part of Letters Patent No. 770,519, dated September 20, 1904.

Application filed January 22, 1904. Serial No. 190,189. (No model.)

To all whom it may concern:

Be it known that I, HIRAM A. Dow, a citizen of the United States, residing at Battle-creek, in the county of Calhoun and State of Michigan, have invented certain new and useful Improvements in Electric Massage-Vibrators, of which the following is a specification, reference being had therein to the accompanying drawings.

10 My invention relates to that class of massage-vibrators which are operated electrically, the object being to provide a light and compact instrument that can be readily carried about and attached to any ordinary lamp-15 socket.

I am aware that more or less cumbersome devices for producing mechanical vibratory action for massage purposes have been devised to operate with flexible cord, pneumatic, 20 and other agents; but the construction and operation of these appliances heretofore necessitated a restricted field, for the reason that the patient must be brought to the fixed station of the machine, which is often inconvenient and in many cases impossible.

25 My improvement consists in providing a strictly portable instrument for the use of physicians, barbers, &c., or patients at their homes, whereby the sick and afflicted may 30 be treated as often and in the manner the nature of the case requires.

My device is arranged to deliver light or heavy and rapid vibrations as desired, as will hereinafter be explained.

35 The application and value of massage vibration in the treatment of nervous and kindred disorders and for stimulating the action at nerve centers, cords, and muscles, as well as promoting circulation in blood vessels that 40 have become sluggish in action, is too well known to those versed in the science to need extended explanation.

In the drawings, Figure 1 is a front elevation of my improved instrument with the 45 handle and a part of the casing in section. Fig. 2 is an enlarged view from below vibrator-bar, showing the eccentric and yoke with the motor-spindle in section. Fig. 3 is an enlarged sectional elevation of the operating 50 parts. Fig. 4 is an enlarged section of the

vibrator-bar with yoke attached. Figs. 5 and 6 are enlarged views showing elastic tips to soften the action. Fig. 7 shows the eccentric embraced within a loose ring to reduce friction at this point. 55

A represents the motor-easing.

B is the handle.

C is the vibrator-bar casing.

D is the motor-easing cap.

E is the upper handle-bracket with ferrule. 60

F is the lower handle-bracket with ferrule.

G is the thumb-button to handle-switch.

H is the coupling attached to the vibrator-bar, to which the bar-tips K are detachably secured by screw-thread engagement. 65

L is the impinging-point of bar-tip, preferably made of an elastic material.

a is the vibrator-bar.

b is the motor-spindle.

c is the eccentric on the upper end of the 70 motor-spindle.

d is the yoke, secured to the vibrator-bar and engaging the eccentric.

e is the switch-stem, which I prefer to make of hard rubber or other non-conducting material. 75

f is a washer fixed in the handle-bore and serves to guide the lower end of the switch-stem and also form a stop to the movement of the switch-plug. 80

g h i are the contact-points of the switch.

o is an opening in the lower handle-ferrule for insertion of the cable-cord.

n p are screws to attach wires of cable-cord to switch-strips t u. 85

x is an insulating-strip between the switch-strips.

s is a coil-spring normally holding the switch-plug out of contact with the points h i. 90

z is a loose ring embracing the eccentric.

As it is obvious that any suitable electric motor may be used to operate the device, it is not deemed necessary to particularize, either by description or illustration, further than to state that I prefer to make the casing A of 95 spherical form and attach the handle-brackets and casing-cap as shown.

The wired connections I make as follows: from lamp-cord one wire to p, the other to motor-terminal, the other motor-terminal to n. 100

The operation is as follows: The handle being grasped and the thumb-button *G* depressed, current is passed to the motor and the motor-shaft *b*, revolving with its terminal eccentric engaging yoke *d*, which is secured to the vibrator-bar, as previously explained, a rapid reciprocating motion is communicated to the latter, which will continue so long as the button is depressed. By providing various bar-tips having different degrees of elasticity and size the force of vibration and the area of surface operated upon may be limited or modified as desired. I may attach a suspending-cord to the upper handle-bracket at *E*, passing vertically over a ceiling-pulley to pendent weight to counterbalance the weight of the machine; but I do not confine myself to this manner of suspension.

Having thus fully described my improvement, what I claim as my invention, and desire to secure by Letters Patent, is—

1. In an electric massage-vibrator, the motor-casing, an eccentric terminal on the motor-spindle above the casing-cap, a vibrator-bar with yoke attached engaging the same, and handle-brackets embracing a hollow handle with inside switch mechanism, substantially as shown and described.
2. In an electric massage-vibrator, a hollow

handle having bracket-arms embracing the handle ends and connected to a spherical motor-casing, having an eccentric on the upper end of its spindle, a yoke engaging the same, a vibrator-bar attached to the yoke, and switch mechanism inclosed within the hollow handle having a projecting thumb-button, substantially as shown and described.

3. In an electric massage-vibrator, the hollow handle, *B*, with inclosed switch mechanism, the bracket-arms *E*, *F*, the vibrator-bar *a*, casing *C*, yoke *d*, eccentric *c*, and coupling *H*, spindle-tip *K*, and motor-casing *A*, substantially as shown and described.

4. In an electric massage-vibrator, a motor-casing of spherical form, having an eccentric on its upper spindle end, a ring loosely embracing the eccentric and engaging a yoke attached to a vibrator-bar, together with bracket-arms supporting a handle having switch mechanism inclosed, substantially as shown and described.

In testimony whereof I affix my signature in presence of two witnesses.

HIRAM A. DOW.
